UNITED STATES PATENT OFFICE.

JOSEPH A. MASHEK, OF OAK PARK, ILLINOIS.

MASSAGE APPARATUS.

1,420,049.

Specification of Letters Patent. Patented June 20, 1922.

Application filed September 10, 1918. Serial No. 253,400.

To all whom it may concern:

Be it known that I, JOSEPH A. MASHEK, a citizen of the United States, and a resident of the city of Oak Park, county of Cook, 5 and State of Illinois, have invented certain new and useful Improvements in Massage Apparatus, of which the following is a specification.

My invention relates to improvements in 10 massage apparatus and has for its object the provision of an improved construction of this character adapted to produce peculiar and beneficial manipulations of the human skin.

15 The invention consists in the combinations and arrangements of parts hereinafter described and claimed.

A further object of the invention is to 20 provide a simple and efficient mounting for the apparatus, capable of permitting various applications thereof.

Other objects will appear hereinafter.

The invention will be best understood by 25 reference to the accompanying drawings forming a part of this specification, and in which,

Fig. 1, is a view showing the apparatus mounted in position for use,

Fig. 2, a detail view taken substantially 30 on line 2—2 of Fig. 1,

Fig. 3, a detail view taken substantially on line 3—3 of Fig. 1,

Fig. 4, a vertical section taken through the massage apparatus proper,

35 Fig. 5, a bottom plan view corresponding to Fig. 4 but with one of the contact pads removed,

Fig. 6, a detail view of one of the contact pads,

40 Fig. 7, a top plan view of a massage apparatus proper shown as detached from its support.

Fig. 8, a horizontal section of the same, and

45 Fig. 9, a bottom plan view of a cam plate employed in the construction.

The preferred form of construction as 50 illustrated in the drawings comprises an angular supporting rod having a horizontal portion 10 and a vertical portion 11 adapted to be adjustably secured by means of clamps 12 to the rear side of a barber chair 13, or the like, and permitting of vertical and angular adjustments of said rod. A supporting bracket comprising a substantially U-shaped clip 14 is provided with a grooved

pulley 15 riding upon the horizontal portion 10 of said rod, stop collars 16 and 17 being arranged as indicated to limit the travel of said pulley. Another clip 18 substantially 60 in inverted U-form is pivoted to the lower end of clip 14 and carries a larger grooved pulley 19, as shown. A flexible elastic suspension element in the form of a helical spring 20 is suspended on pulley 19, and 65 carries at its lower ends grooved pulleys 21 riding upon a grooved supporting track or bale 22 secured to the upper side of a supporting plate 23 having a centrally upstanding stud shaft 24 formed integrally therewith. The plate 23 is provided on its upper side with a plurality of pairs of guide lugs or ears 25, the members of each pair arranged in radial alinement as indicated, there being four pairs of these guide lugs 75 employed. A guide rod 26 is mounted in each pair of lugs 25 to slide radially with reference to shaft 24 and carries a transverse rod 27 having eccentric trunnions 28 at its ends upon which are mounted guide 80 rollers 29 running upon tracks or surfaces 30 provided on the upper side of plate 23, said rollers tending to alleviate friction and facilitate easy reciprocation of the guide rods 26. Each of the rods 26 carries a de- 85 pending threaded stud 31 passing through a corresponding slot 32 in plate 23 and carrying at its lower end a sponge rubber contact pad 33, as shown. The plate 23 is upwardly convex in form and the guide rods 90 26 are arranged to slide parallel with its upper surface, so that the pads 33 are arranged and adapted to contact with a slightly convex surface such as the scalp or face of a person, and to travel substantially 95 parallel with said convex surface in constant contact therewith.

Each of the rods 26 also carries an up- 100 standing threaded stud 34 impinging against the corresponding rod or pin 27 and serving as a means for locking the same in position after angular adjustments to adjust the contact between rollers 29 and tracks 30. At its upper end each of the studs 34 carries a conical roller 35 arranged to run in a cam 105 groove 36 in the under side of a cam plate 37 loosely mounted upon stud shaft 24, said cam groove being shaped and designed to cause simultaneous inward and outward radial movements of rods 26 and consequently 110 of contact pads 33. The edges 38 of cam groove 36 are bevelled, as shown, and the

rollers 35 are rendered adjustable by means of set screws 39, so that adjustments may be readily made to compensate for wear and take up lost motion between the rollers and 5 cam grooves.

The periphery of cam plate 37 is provided with a friction surface contacting with a friction wheel 40 on the motor shaft of electric motor 41. Motor 41 is carried by rocker 10 arm 42 on a rocker shaft 43 mounted in a bracket 44 secured to the upper end of stud shaft 24, and a tension spring 45 serves to maintain yielding contact between friction wheel 40 and the periphery of cam 37. Motor 41 is supplied with current through a flexible cord or connection 46, which permits of ready movement of the apparatus in use.

By this arrangement it will be observed 20 that upon rotation of plate 37 under the influence of motor 41, the contact pads 33 will be caused to simultaneously approach and recede from each other, thus adapting them to impart alternate pinching and stretching 25 action to the skin during operation. This is a highly desirable manipulation of the skin, and closely approaches that which may be accomplished by use of the hands. The form of support for the apparatus counter- 30 acts the weight thereof, permitting of the ready application and manipulation thereof in any desired direction or any desired position.

While I have illustrated and described 35 the preferred form of construction for carrying my invention into effect, this is capable of variation and modification without departing from the spirit of the invention. I, therefore, do not wish to be limited to the 40 precise details of construction set forth, but desire to avail myself of such variations and modifications as come within the scope of the appended claims.

Having described my invention, what I 45 claim as new and desire to secure by Letters Patent is:—

1. A massage apparatus comprising a support; a convex member carried by said support; contact pads carried by said member, 50 said pads being mounted to move toward and away from each other; and an operating member engaging said pads, said operating member being provided with a cam groove for moving said pads toward and away 55 from each other, substantially as described.

2. A massage apparatus comprising a support; a plurality of contact pads on said support arranged to contact with a convex surface and mounted to slide toward and 60 away from each other substantially along said surface; and an operating member having a cam groove formed therein adapted to simultaneously move said pads toward and away from each other, substantially as de- 65 scribed.

3. A massage apparatus comprising a support; a central shaft on said support; slides surrounding said shaft and radiating therefrom; contact pads on said slides; and an operating member loosely embracing said shaft 70 for operating said slides simultaneously toward and away from each other, substantially as described.

4. A massage apparatus comprising a support; a central shaft on said support; slide 75 members surrounding said shaft and radiating therefrom; contact pads adjustably mounted on said slide members and a cam member loosely embracing said shaft for operating said slide members simultaneously 80 toward and away from each other, substantially as described.

5. A massage apparatus comprising a support; a central stationary shaft on said support; convexly curved slides arranged 85 around said shaft and radiating therefrom; contact pads on said slides; and means revolvably mounted on said shaft for operating said slides simultaneously toward and away from each other, substantially as described. 90

6. A massage apparatus comprising a support; a central shaft on said support; convexly curved slides arranged around said shaft and radiating therefrom; contact pads on said slides; a cam on said shaft operatively connected with said slides and arranged to operate said slides simultaneously toward and away from each other; and frictionally engaging means for rotating said cam, substantially as described. 100

7. A massage apparatus comprising a support; a central shaft on said support; slide members surrounding said shaft and radiating therefrom; contact pads on said slide members; an operating disc loosely embracing said shaft; a cam groove formed in said disc adjacent the periphery thereof; and cam rollers on said slide members engaging said groove for operating said slide members, substantially as described. 105

8. A massage apparatus comprising a support; a central upstanding stud shaft formed integrally with said support; a plurality of pairs of guide lugs on the upper side of said support, the members of each pair being arranged in radial alignment with each other; a guide rod slidably mounted in each pair of lugs to slide radially with reference to said shaft; a transverse rod on each of said guide rods having eccentric trunnions at its ends; guide rollers on said trunnions, there being track surfaces on the upper side of said support; a depending threaded stud threaded in each guide rod, there being a corresponding slot in said support; a contact pad at the lower end of each of said depending threaded studs; an upstanding threaded stud on each of said guide rods impinging against the corresponding transverse rod; a conical cam roller adjustably mounted on the upper 115 120 125 130

end of each of said upstanding studs; a cam on said central stud shaft provided with a cam groove operating said cam rollers simultaneously toward and away from each other; an electric motor supported on said stud shaft; and a friction drive wheel on said motor contacting with the periphery of said cam, substantially as described.

In testimony whereof I have signed my name to this specification in the presence of 10 two subscribing witnesses.

JOSEPH A. MASIEK.
